INVENTOR:

BY Drake & Co., ATTY'S.

UNITED STATES PATENT OFFICE.

DAVID WALKER, OF NEWARK, NEW JERSEY.

DESIGN FOR A STAIR-CARPET BUTTON.

SPECIFICATION forming part of Design No. 19,366, dated October 22, 1889.

Application filed September 25, 1889. Serial No. 325,081. Term of patent 14 years.

To all whom it may concern:

Be it known that I, DAVID WALKER, a citizen of the United States, residing at Newark, in the county of Essex and State of New Jersey, have invented and produced a new and original Design for Stair-Carpet Fasteners; and I do hereby declare the following to be a full, clear, and exact description of the invention, such as will enable others skilled in the art to 5 which it appertains to make and use the same, reference being had to the accompanying drawings, and to letters of reference marked thereon, which form a part of this specification. 10 15 Figure 1 is a front view of a stair-carpet fastener; and Figs. 2 and 3 are sectional views of the same, taken through line *x*, embracing my design. The leading feature of the design consists 20 25 of a stair-carpet fastener having the configuration hereinafter described.

a indicates the center of the fastener, which, when viewed endwise, is shown to be convex on its outer face and triangular in general outline. At the sides of said convex center 25 part the fastener tapers, as at *c c*, toward the ends. At the upper and lower edges the fastener is provided with flange-like configurations *b b*.

What I claim is—

The design for a stair-carpet fastener herein shown and described, comprising a stair-carpet fastener which is convex at the center, tapering toward the ends, as at *c c*, and flange-like at the edges, substantially as set forth. 30 35

In testimony that I claim the foregoing I have hereunto set my hand this 23d day of July, 1889.

DAVID WALKER.
